UNITED STATES PATENT OFFICE

2,610,709

BUILDING CONSTRUCTION

Thaddeus B. Hurd, Detroit, Mich., assignor to
 National Steel Corporation, a corporation of
 Delaware

Application September 26, 1946, Serial No. 702,833

6 Claims. (Cl. 189—1)

1

This invention relates generally to building construction and more particularly to building elements for connecting together several structural building members.

It is an object of the present invention to provide new and improved building construction in which the members thereof readily fit together in interlocking relation reducing time and consequently costs of building erection.

Another object of the invention is to provide a new and improved building connector member for readily connecting together a number of building elements.

Another object of the invention is to provide a new and improved building framing construction in which load supporting, exterior wall beams are eliminated.

Another object of the invention is to provide building framing, the members of which readily fit together and hold each other in place without need of additional fasteners.

Other objects of the invention will be apparent from the following detailed description taken in connection with the accompanying drawings in which:

Figure 1 is a fragmentary, isometric view of an exterior corner of a building, embodying features of the present invention;

Figure 2 is a fragmentary, isometric view of the building framework;

Figure 3 is an isometric view of a building element of the framework;

Figure 4 is a fragmentary vertical sectional view of the building, taken along the line 4—4 of Figure 1;

Figure 5 is a fragmentary, cross-sectional view of a corner of the building, taken along the line 5—5 of Figure 1;

Figure 6 is a fragmentary, isometric view of another building construction similar to the building construction of Figure 1;

Figure 7 is a fragmentary, isometric view of the framework of the building of Figure 6;

Figure 8 is a vertical cross-sectional view of the building, taken along the line 8—8 of Figure 6;

Figure 9 is a horizontal sectional view of the building framework, taken along the line 9—9 of Figure 8;

Figure 10 is an isometric view of a building element of the building of Figure 6, similar to the building element of Figure 3; and

Figure 11 is a cross-sectional, detail view of the building of Figure 6, taken along the line 11—11 of Figure 8.

Referring to the drawings by characters of

2

reference and first to the building construction of Figures 1 to 5 inclusive, this building includes columns or studs 10, exterior wall beams or girders 11, joists 12, connector or bracket members 13, joist spacer members 14 and outlooker members 15. The columns 10 extending upwardly from any suitable foundation (not shown) support the girders 11 which extend between and connect or tie the upper ends of the columns 10 together around the walls of the building. The building includes similar walls opposite to the walls shown. The joists 12, extending between opposite side wall girders 11 are supported at their opposite ends by the brackets 13 which in turn seat directly on the supports or girders 11 in spaced relation therealong. These brackets 13 are located and held in relative spaced relation longitudinally of the girders 11 by the spacer members 14 which extend between the brackets, longitudinally of and immediately above the girders 11. Thus, the spacer members 14, through the brackets 13 maintain the joists 12 in relative laterally spaced relation. Each of the brackets 13 includes one of the outooker members 15 which, extending outwardly from or overhanging the walls of the building, constitutes supports for eave structure. This overhang or eave structure may be provided only at the roof of the building or, if desired, may be provided at each floor.

The girders 11, used in the present construction are preferably steel members of unusual depth so that the supporting columns 10 therefore can be widely spaced apart without danger of the girders sagging under the load of the upper structure. These girders 11 may comprise a deep web 16, a lower seating flange 17, an upper supporting flange 18 and end connector flanges 19. Extending horizontally between the columns 10 in vertical coplanar relation therewith, the girders 11 may be secured at their end connector flanges 19 to the sides of the columns by self-threading screws or by any other suitable means. In certain types of small buildings, it may only be necessary to have columns at the corners thereof, whereas in larger buildings one or more intermediate columns will be desirable.

Any suitable type of joist may be used in this building, the joists 12 of the present construction being steel, nailable members, each including a channel having a web 20, an upper floor flange 21 and a lower ceiling flange 22. To the back of the channel web 20 is welded an upper angle member 23 and a lower angle member 24 forming with the channel member, a composite structural member of general I-beam cross-section.

The angle members 23, 24 are spaced from one side surface of the channel web 20 providing nail receiving slots wherein the nails are clinched due to the sinuous form of the slots.

Each of the connector members or brackets 13 comprises a number of joined together retainer channels, namely a joist retainer channel or hanger 25 and spacer member retainer channels 26. The bracket 13 includes an outlooker 15 which is also a retainer channel. The joist retainer channel 25 comprises a lower horizontal seat portion 27 which is joined to an upper seating portion 29 by connecting portions or sides 30 of the joist retainer channel 25. The upper seating portion 29 is offset in stepped relation to the lower joist seat portion 27 to rest on the upper supporting flange 18 of the girders 11. This upper seating portion 29 of the bracket 13 joins with the channel outlooker 15 which aligns in end to end relation with the joist receiving channel 25. The channel outlooker 15 comprises a bottom web 29' and upstanding sides 32, the sides 32 joining or being integral respectively with the sides 30 of the joist receiving channel 25. The spacer member retainers or channels 26 each comprises a seat or web 28 and upstanding retaining sides or flanges 31. The spacer member retainers 26 are disposed on opposite sides of the bracket 13 adjacent the upper seating surface 29 thereof so as to immediately overlie the wall girders 11. These channel retainers 26 extend laterally from the bracket side flanges 30 to which ends of the channels may be butt welded, the seats 28, 29 and 29' being in the same horizontal plane. Further, the channel retainers 25, 26 and the channel outlooker 15 are relatively arranged so that the upper edges of their sides 30, 31 and 32 respectively, are in the same horizontal plane.

Received in each of the channel outlookers 15 is a nailable member 34 to which to secure the eave structure 35 which may be a continuation of the building flooring or roofing, as the case may be. This nailable member 34 may be of the same general construction as the joists 12 with which they align, but need not be as deep. Thus, the bottom seat 27 of the joist retainer is disposed below the upper seating portion 29' of the bracket a distance substantially equal to the differential in the depths of the joist 12 and the nailable member 34, so that the upper surfaces of the joists and of the nailable members 34 will be in the same horizontal plane, which is preferably coincident with the upper edges of the retainer channels. An extended portion or lip 37 of the retainer seat 27 is bent up against the inner surface of a downturned edge portion 38 of the upper girder flange (see Figure 4), restraining inward movement of the connector member or bracket 13. Adjacent the outer end of each of the channel outlookers, the sides 32 thereof are bent inwardly, as at 40, the web 29 continuing beyond the bent-in side portions and having an upturned end portion. This forms a channel-like retainer or holder at the end of the outlooker for an eaves trough 42 which may be fitted tightly therein and held in place without need of additional securing means.

The bracket spacer members 14 are preferably of general channel form having a bottom seat or web 44 and upturned sides 45 provided with in-turned flange portions 46. As shown, the upper surfaces of the spacer member flange portions 46 are preferably coplanar or flush with the upper edges of the brackets 13. Opposite end portions of these spacer members 14 are preferably of reduced size providing a shoulder 47 around the 75

sides and web of the channel. The reduced end portions of the spacer members 14 snugly fit into the channel retainers 26 to provide a weather-tight connection, the shoulders 47 engaging the ends of the retainers as stops. Preferably, the spacer members 14 seat on the upper flange of the girders 11 as well as in the retainers 26, and in addition to spacing apart the brackets 13, serve to close the opening between the upper surface of the girders and the overhang or eave. The walls of the building may be constructed of plywood panels 48 or other suitable means extending upwardly from the building foundation to the under sides of the spacer members 14 and of the spacer retainers 26. At the building corners, the panel joints each may be covered by an angle finishing strip 49.

In the erection of the building, assuming the columns 10 and connecting girders 11 are in place, the connector members or brackets 13 may next be positioned on and spaced in approximate relation along the girders 11 between columns with a bracket preferably located at each column. Next, the spacer members 14 may be added to the structure, positioning their opposite ends respectively in the bracket retainers 26 with the spacer stop shoulders 47 tight against the ends of the retainers. With the brackets 13 properly spaced apart by the spacer members 14, the joists 12 may now be set in place with opposite end portions thereof respectively seating in opposite retainers 25 of the brackets 13. Next, the nailable members 34 may be set in place in the channel outlooker 15 and the flooring or roofing, as the case may be, applied and nailed in place to the joists 12 and to the eave nailable members 34. At the roof, the eave troughs or gutters 42 may be pressed down into the holders therefor carried by the outer ends of the outlooker 15.

From the above description, it will now be appreciated that I have provided a new and improved connector member for connecting together several structural members of a building. By reason of this connector member or bracket it will be seen that the joists, joist spacer members and the outlooker can be readily assembled by more or less merely setting them in their proper places, since they interfit, relatively holding each other in place and to the girders without need of the usual fasteners or securing means.

Referring now to the building construction of Figures 5 to 11 inclusive, there is shown a building framework which, unlike the previously described building, omits load supporting wall beams or girders. Instead of wall beams or girders, the present building framework includes a plurality of laterally spaced bents, each comprising a pair of oppositely disposed supports or columns 50, a spanning joist 51 and a pair of connector members or brackets 52. Only a portion of the bents is shown in the drawings. The bents are connected together in relatively laterally spaced relation by spacer members 53 which extend between adjacent bents inwardly of the columns 50, the spacer members 53 being connected to the columns by the brackets 52. The brackets 52 are secured to the inner sides of the column and each of the brackets carries an outlooker member 54 extending outwardly in alignment with respective joists.

The columns 50 each comprises a pair of channels 55 spaced apart in back-to-back relation and secured together by inner and outer plates 56 welded respectively to the inner and outer channel flanges. The joists 51 may be the same

In construction as the joists 12 of the previously described building and therefore like parts are designated by like numerals to avoid unnecessary repetitious description.

The connector members or brackets 52 each comprises a joist retainer member 58, spacer member retainers 59 and a retainer 60 for the outlooker member 54. The brackets 52 may be made of sheet metal bent or formed to have a vertical connecting portion 61, an upper, outwardly bent seating portion 62 and a lower inwardly bent or seat portion 63. The seating portion 62 is adapted to rest on the upper end of a column. The upper horizontal plate portion 62 supports the outlooker retainer 60 which is of channel form having upstanding oppositely disposed restraining sides 65. A vertically extending pair of plate members 66 seating at their lower edges on the lower horizontal plate portion 63 constitutes the restraining sides of the joist retainer member 58, the plate members 66 dividing the lower horizontal plate portion 63 into an intermediate seat 67 for the joist and opposite end seats 68 for the spacer members 53. The upper seating portion 62 of the bracket is vertically spaced from the lower joist seat portion by the connecting portion 61, a distance substantially equal to the differential of the depths of the joist and outlooker member. The vertical plate members 66 may be welded along their lower edges to the lower horizontal plate portions 63 and along vertical edges to the vertical plate portion 61 intermediate the side edges thereof. Between the plate members 66, the vertical plate portion 61 of the brackets may be provided with apertures 70 to receive bolts 71 for securing the brackets to the inner faces of the columns 50. Outwardly of the bracket plate members 66, the plate portion 61 is provided with apertures 72 to receive bolts 73 securing the spacer members 53 to the brackets. In the plate members or sides 66 of the joist retainer 58, apertures 75 may be provided to receive bolts 76 extending through the joist web to limit longitudinal movement of the joists 51, lateral movement being limited by the restraining sides 66 of the retainer. Also, aligning apertures 77 may be provided in the upstanding restraining sides 65 of the outlooker retainers 60 to receive bolts 78 to connect the bracket and outlooker member together.

The spacer members 53 are of general channel form having a web 80, a lower seating flange 81 and an upper supporting flange 82. Flooring or roofing 83 and ceiling material 84 may be attached to the spacer members 53 by snap-in fasteners 85 adapted to frictionally engage in spring channels 86 formed in the top and bottom flanges of the spacer members 53. As shown, the flooring or roofing 83, as the case may be, extends outwardly providing an overhang or eave 87 supported on the upper surfaces of the outlooker members 54. These outlooker members 54 are preferably of channel-form having a bottom seat or web 90 and upstanding restraining sides 91. At its outer end, the outlooker web 90 extends beyond the sides 91 and is bent up, as at 92, providing a retainer for an eaves trough 93. Retained in the channel outlooker 54 is a nailable member 94. The roof or floor 83 is nailed to the joists 51 and the overhang or eave 87 is nailed to the nailable member 94 in the channel outlookers 54, the joist and the nailable member 94 presenting substantially flush upper bearing surfaces due to the vertical spacing of their bracket seats.

In erecting this building, the bents may be assembled flat on the ground and then be raised and connected together by the spacer members 53. In assembling the bents, the connector members or brackets 52 are first bolted to the inner sides of a pair of the columns 50 with the outlooker retainer 60 immediately above the upper ends of the columns. The joist 51 may then be positioned with its opposite ends engaged respectively in the pair of bracket retainers 58 and be secured thereto by the bolts 76. In connecting the raised bents together, the spacer members 53 are positioned with their opposite ends seating on the seats 68 of adjacent brackets to which the spacer members may be secured by the bolts 73. With the outlookers 54 secured to their respective brackets 52 in the retainer channels 60 by the bolts 78, the nailable members 94 may be set in the outlookers and the eave troughs set in the retainers at the outer ends of the outlookers. The flooring or roofing 83 may then be nailed to the joist and the overhang or eaves 87 be nailed to the nailable members 94 in the outlookers 54.

It will now be seen that the connector members or brackets 52 like the connector members or brackets 13 of the previously described building provide for ready assembly of the building elements into a complete building framework in a manner decreasing time and costs of erection. For example, the provision of these brackets 13 makes it possible in building erection to simply set the joists, spacer members and the outlooker supported nailable members in place, in the retainers or seats of the brackets which interconnect the parts and connect them to the columns.

I claim:

1. In building construction the combination comprising, a support having a downwardly turned flange terminating in a lower free edge, a joist extending away from the support, a connector member supported on the support presenting a seat supporting an end portion of the joist, and attachment means formed out of a portion of the connector member, said attachment means extending about and engaging the free edge of the support flange and holding the connector member against movement in either direction longitudinally of the joist.

2. A connector member for use in connecting building members together comprising, a channel retainer having side walls and a bottom web providing a seat to receive an end portion of a joist, a channel outlooker above the seat of the channel retainer extending from and in alignment with the channel retainer, said outlooker including side walls integrally joined to the side walls of the channel retainer and a bottom web, and channel retainer members carried by and extending from opposite sides of the channel outlooker to receive end portions of joist spacer members, each channel retainer member including spaced sidewalls and a bottom web, the bottom webs of the outlooker and the channel retainer members being coplanar and above the bottom web of the channel retainer.

3. A connector member for use in connecting building members together comprising, a channel retainer having side walls and a bottom web providing a seat to receive an end portion of a joist, a channel outlooker above the seat of the channel retainer extending from and in alignment with the channel retainer, said outlooker including side walls integrally joined to the side walls of the channel retainer and a bottom web, and channel retainer members carried by and

extending from opposite sides of the channel out-looker to receive end portions of joist spacer members, each channel retainer member including spaced side walls and a bottom web, the bottom webs of the out-looker and the channel retainer members being coplanar and above the bottom web of the channel retainer, and the upper edges of all of said side walls being coplanar.

4. In a building structure, the combination comprising, a support, a connector member positioned on the support and connected to the support, the connector member including a channel retainer extending inwardly of the support and having a bottom web forming a joist seat and side walls extending upwardly from the bottom web, a channel out-looker above the bottom web of the channel retainer extending outwardly of the support and in alignment with the channel retainer, said channel out-looker including a bottom web and side walls integrally joined to the side walls of the channel retainer, and channel retainer members carried by and extending from opposite sides of the channel out-looker, each channel retainer member including spaced side walls and a bottom web, the bottom webs of the channel out-looker and the channel retainer members being coplanar and above the bottom web of the channel retainer, a joist having an end portion seating on the bottom web between the side walls of the channel retainer, laterally extending joist spacer members each having an end portion received by a respective one of the channel retainer members, and an out-looker beam in the channel out-looker on the bottom web of the channel out-looker.

5. In a building structure, the combination comprising, a support, a connector member positioned on the support and connected to the support, the connector member including a channel retainer extending inwardly of the support and having a bottom web forming a joist seat and side walls extending upwardly from the bottom web, a channel out-looker above the bottom web of the channel retainer extending outwardly of the support and in alignment with the channel retainer, said channel out-looker including a bottom web and side walls integrally joined to the side walls of the channel retainer, and channel retainer members carried by and extending from opposite sides of the channel out-looker, each channel retainer member including spaced side walls and a bottom web, the bottom webs of the channel out-looker and the channel retainer members being coplanar and above the bottom web of the channel retainer, a joist having an end portion seating on the bottom web between the side walls of the channel retainer, laterally extending joist spacer members each having an end portion received by a respective one of the channel retainer members, and an out-looker beam in the channel out-looker on the bottom web of the channel out-looker, all of said side walls having upper coplanar edges.

of the channel retainer, a joist having an end portion seating on the bottom web between the side walls of the channel retainer, laterally extending joist spacer members each having an end portion received by a respective one of the channel retainer members, and an out-looker beam in the channel out-looker on the bottom web of the channel out-looker, the top of the joist and the top of the out-looker beam being coplanar.

6. In a building structure, the combination comprising, a support, a connector member positioned on the support and connected to the support, the connector member including a channel retainer extending inwardly of the support and having a bottom web forming a joist seat and side walls extending upwardly from the bottom web, a channel out-looker above the bottom web of the channel retainer extending outwardly of the support and in alignment with the channel retainer, said channel out-looker including a bottom web and side walls integrally joined to the side walls of the channel retainer, and channel retainer members carried by and extending from opposite sides of the channel out-looker, each channel retainer member including spaced side walls and a bottom web, the bottom webs of the channel out-looker and the channel retainer members being coplanar and above the bottom web of the channel retainer, a joist having an end portion seating on the bottom web between the side walls of the channel retainer, laterally extending joist spacer members each having an end portion received by a respective one of the channel retainer members, and an out-looker beam in the channel out-looker on the bottom web of the channel out-looker, all of said side walls having upper coplanar edges.
